To all whom it may concern:

Be it known that I, Jack Kirschner, a citizen of the United States of America, residing in Manhattan, county of New York, and State of New York, have invented a new, original, and ornamental Design for a Dress, of which the following is a specification, reference being had to the accompanying drawing, forming part thereof, wherein,

The zigzag lines on the sides of the tab at the cuff portion of the sleeves represent shirring.

The diagonal lines extending up the sleeves represent an opening.

The extended portions at the sides of the skirt in Figure 1 represent slits.

I claim:

The ornamental design for a dress, substantially as shown and described.
